UNITED STATES PATENT OFFICE

SYLVESTER M. DUNLAP, OF DES MOINES, IOWA, ASSIGNOR OF ONE-HALF TO C. H. DAY,
OF KELLOGG, IOWA

COOLING DEVICE FOR FOOD CABINETS

Application filed September 23, 1929. Serial No. 394,512.

The object of my invention is to provide an improved means of simple, durable and inexpensive construction which may be used in connection with a food cabinet which will automatically reduce the temperature of the air within the cabinet without the use of power operated mechanism.

A further object is to provide means for reducing the temperature of a food cabinet, employing a sunken well or similar reservoir, whereby evaporation of the moisture within the well as the air is passed through the same and through the food cabinet is utilized to reduce the temperature of the circulating air, and to provide in connection therewith means for automatically circulating said air.

A further object is to provide in connection with that type of device for reducing the temperature of air within a food chamber, employing a sunken well and means for circulating air through said well and through said food chamber, improved means whereby the temperature of the circulating air may be further reduced by supplying cold water to a suitable container within the air passages.

Another object is to provide in connection with that type of a device employed for reducing the temperature of the air within a food cabinet, in which is included a sunken well and means for circulating air through the well and the food cabinet, whereby the evaporation of the moisture within the well reduces the temperature of the circulating air, improved means whereby the moisture is artificially supplied to the well when the natural source of moisture is cut off.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a vertical sectional view of my improved device, illustrating the manner in which a food cabinet is applied to a building, which is also in section.

Figure 2 is a sectional view of the food cabinet.

Figure 3 is a detail sectional view taken on the line 3-3 of Figure 1.

Figure 4 is an enlarged detail view of the valve mechanism used in connection with the water supply tank.

Referring to the accompanying drawings I have used the reference numeral 10 to indicate a building in which a food cabinet 11 is mounted. Said cabinet is provided with a food chamber 12 and suitable doors 13 and 14 through which food may be placed in the cabinet. The cabinet is also provided with suitable shelves 15 having openings 16 through which air may circulate.

The cabinet is provided with a layer of heat insulating material 17. The inner surface of the cabinet is provided with a sheet metal wall 18 which may be finished in enamel or other rust resisting material.

The upper end of the cabinet 11 is provided with an opening 19 in which is mounted a pipe 20. The upper end of the pipe 20 is provided with a suitable hood 21. The pipe 20 and the hood 21 are preferably mounted adjacent to the roof of the building 10 in such a manner that air circulating past the upper end of the pipe 20 will create a suction in said pipe, causing the air within the food cabinet to be drawn through an inlet opening 22 in the bottom of the cabinet. Said inlet opening 22 is provided with a pipe 23 extending into the ground 24 and communicating with one end of an air tank 25. The opposite end of the air tank 25 is connected with the lower end of a well 26 by means of a suitable pipe 27. The well 26 has a wall 28 formed of brick or other porous material, whereby moisture from the surrounding ground will be drawn to the inner surface of the wall by capillary attraction.

By this arrangement it will be seen that upward movement of the air currents in the pipe 20 will be caused to be moved downwardly through the well 26 through the pipe 27, the tank 25 and the pipe 23. The movement of the air through the well 26 will cause the moisture collected on the inner surface of the well 28 to be evaporated, causing the temperature of the circulating air to be re-

duced, and the temperature in the interior of the food chamber also reduced.

It sometimes happens that during dry seasons the ground surrounding the well becomes dry, in which case the moisture supplied to the wall 28 ceases and consequently reduction of the temperature of the air within the food chamber also ceases. To overcome this difficulty I have mounted in the air chamber 25 a water tank 29 considerably smaller in diameter than the air chamber, to permit air moving through the air tank to pass around the water tank, whereby the temperature of the air will be reduced. Suitable brackets 30 are provided for supporting the tank 29.

A pipe 31 is provided having its lower end connected to the tank 29 and its upper end projecting upwardly through the upper surface of the ground. Said pipe provides means whereby water may be supplied to the tank 29. The tank 29 is also provided with an outlet pipe 32 which extends through the walls of the tank 25 terminating at a point adjacent to the well 26. A valve 33 is provided for the pipe 32, said valve being mounted on a lever 34 connected to the end of the tank 29 by a pivot 35. The free end of the lever 34 has a wire or rod 36 which extends upwardly through the pipe 31 having its upper end secured to a cap 37.

It will readily be seen that the water within the tank 29 will become warmed to the temperature of the incoming air, at which time it is desirable to discharge the water through the pipe 32 by simply elevating the cap 37, which will cause the free end of the lever 34 to be elevated and the valve 33 lifted from the pipe 32. The water will then be discharged into the ground adjacent to the lower end of the well 28, and a portion of the discharged water will then be drawn through the wall of the well by capillary attraction, and will assist in cooling the circulation of air to the well by evaporation in the manner above described.

A suitable cover 38 may be provided for the well 26, said cover being spaced above the upper end of the wall 28 by suitable brackets 39, whereby air will be permitted to enter the well through suitable openings 40. The cover 38 prevents the well from becoming filled with trash and foreign substances. The cover 38 should be detachably mounted so that the well may be cleaned when necessary.

Thus it will be seen that I have provided a cooling device for food cabinets of simple, durable and inexpensive construction, in which all mechanically operated mechanism is eliminated, and in which the cooling of the food cabinet may take place at comparatively no expense to the owner, and requires little or no attention.

I claim as my invention:

1. In combination, a food cabinet, an air well in the ground having a porous lining, an air tank supported under the ground and in communication with said air well and said food cabinet, a water tank in said air tank, a supply pipe for said water tank, an outlet pipe for said water tank, a valve for said outlet pipe, and means for actuating said valve from a point above the ground surface. 75

2. A food cabinet, an air well in the ground having a porous wall, an air tank communicating with the lower end of said air well, a water tank within said air tank, a supply pipe for said water tank having one end extending upwardly through the upper surface of the wall, an outlet pipe for said water tank, a valve for said outlet pipe, a lever for moving said valve to open and close said outlet pipe, a wire connected to one end of said lever and extending upwardly through said supply pipe and terminating beyond its upper end, and means for circulating air through said well, said air tank and said food cabinet. 85

3. In combination, a food cabinet, an air well, an air tank supported under the ground and in communication with said air well and said food cabinet, a water tank in said air tank, a supply pipe for said water tank, an outlet pipe for said water tank, and a valve 90 for said outlet pipe.

4. In combination a food cabinet, an air well, an air tank supported under the ground and in communication with said air well and said food cabinet, a water tank in said air tank, a supply pipe for said water tank, an outlet pipe for said water tank, and a valve 100 for said outlet pipe, the discharge end of said outlet pipe terminating in the ground near the lower end of said well. 105
